UNITED STATES PATENT OFFICE.

AUGUST PUGGEL, OF SCHWELM, GERMANY.

POLISHING-MACHINE FOR WOODWORK.

995,179.

Specification of Letters Patent. Patented June 13, 1911.

Application filed September 19, 1910. Serial No. 582,630.

To all whom it may concern:

Be it known that I, AUGUST PUGGEL, a subject of the King of Saxony, and resident of Schwelm, in the Province of Westphalia, 5 German Empire, have invented new and useful Improvements in Polishing-Machines for Woodwork, of which the following is a specification.

The invention relates to a polishing machine for wood work of the kind in which a 10 polishing ball is operated by a flexible shaft or the like and, in a controllable manner, automatically supplied with polish from a receptacle and provided with a handle loosely 15 surrounding the shaft.

In polishing machines hitherto known an inconvenience arose from the fact that the receptacle containing the polish rotated together with the ball so that the polish was 20 continuously hurled during the polishing operation. It was, therefore, difficult to control the supply of polish from the continuously rotating receptacle during the polishing operation.

25 The present invention consists in that the polish receptacle is rigidly connected with the handle loosely surrounding the flexible shaft so that the polish receptacle is at rest during the rotation of the polishing ball. 30 Therefore, the polish is not hurled and its supply may be easily controlled without danger.

In the drawings Figure 1 is a vertical section of a polishing machine according to 35 the invention. Fig. 2 shows a modification.

In the constructional form according to Fig. 1 the spindle *a* is at *b* connected with a flexible shaft *c*. At the lower end of the spindle *a* a disk *d* is secured by means of a screw 40 *e*. The edge *f* of the disk *d* is turned down, as shown, and a sieve *g* is attached to the turned down edge *f* of the disk *d*. The sieve *g* is provided with the polishing ball *h*.

The spindle *a* is surrounded by a tube *i* 45 which is rigidly connected with the disk *d*. At the upper and lower end the tube *i* is provided with annular notches *k* which form bearings for the handle *l* arranged for operating the polishing tool. The handle *l* 50 forms a support for the receptacles *m m'* containing alcohol and polish. These receptacles *m m'* are provided with openings *n n'* by which the polish and alcohol is supplied into the space *o* between the spindle *a* 55 and the tube *i*. Said space *o* is at its lower

end in communication with the box formed by the disk *d* and the sieve *g*. The openings *n n'* may be opened or closed by means of adjustable valves for controlling the supply of the alcohol and polish. In the constructional form shown the controlling device consists of perforated tubes *p p'* which are guided in the openings *n n'* and at their lower ends provided with disks *r r'*. The tubes *p p'* are usually pressed against the 60 base plates of the receptacles *m m'* by means of springs *s s'*. As will be evident the receptacles *m m'* are during the operation of the polishing machine at rest.

In the modification according to Fig. 2 the 70 spindle *a* is connected with an electro-motor *t*. This electro-motor *t* is surrounded by a receptacle *m* for the polish, which is supplied by means of the valves *r* through the hollow handle *l* to the polishing ball *h* provided at the lower end of the spindle *a*. The handle *l* is also rigidly connected with the receptacle *m* as in the constructional form 75 according to Fig. 1.

The construction of the other parts of the 80 machine is substantially the same as in Fig. 1.

I claim:

1. The combination with a wood-work 85 polishing machine having a polishing ball, a hollow handle therefor, a rotary spindle connected with the polishing ball and rotating freely within the handle, and driving means for said rotary spindle; of an annular receptacle containing the polish, 90 said receptacle being rigidly carried at the upper end of said handle and surrounding the driving means, an annular space between said handle and spindle forming a conduit for supplying polish from the receptacle to the polishing ball, and valve means for controlling the supply of polish.

2. The combination with a wood-work 100 polishing machine having a polishing ball, a hollow handle therefor, and a rotary spindle connected with the polishing ball and rotating freely within the handle, of an electric motor mounted upon and supported by said handle, said electric motor being connected to the spindle, an annular receptacle containing the polish, said receptacle being rigidly carried at the upper end of said handle and surrounding the electric motor, an annular space between said handle and spindle forming a conduit for sup- 105 110

plying polish from the receptacle to the polishing ball, and valve means for controlling the supply of polish.

3. The combination with a wood-work 5 polishing machine, having a polishing ball, a hollow handle therefor, a rotary spindle connected with the polishing ball and rotating freely within the handle, and driving means for said rotary spindle; of an annular receptacle containing the polish, 10 said receptacle being rigidly carried at the upper end of said handle and surrounding the driving means, an annular space between said handle and spindle forming a conduit for 15 supplying polish from the receptacle to the polishing ball, valve openings in the bottom of said receptacle, said valve openings communicating with said annular space, and spring controlled means operated from 20 the exterior of said receptacle for opening and closing said valve openings.
4. The combination with a wood-work

polishing machine having a polishing ball, a hollow handle therefor a rotary spindle connected with the polishing ball and rotating freely within the handle, and driving means for said rotary spindle; of an annular receptacle containing the polish, 25 said receptacle being rigidly carried at the upper end of said handle and surrounding the driving means, a bush within the handle 30 and rotating with said spindle and polishing ball, an annular space between said bush and spindle forming a conduit for supplying polish from the receptacle to the polishing ball, and valve means for controlling the supply of polish.

In witness whereof I have hereunto set my hand in the presence of two witnesses.

AUGUST PUGGEL. [L. S.]
